TRENCHING MACHINE

Glenn W. McIninch, Omaha, Nebr., assignor to
 Auburn Machine Works, Inc., Auburn, Nebr., a
 corporation of Nebraska

Application April 4, 1950, Serial No. 153,967

2 Claims. (Cl. 37—191)

1

The present invention pertains to improvements in trench-digging machines and more particularly to digger-bits and holders therefor.

It is an object of the present invention to provide a novel digger-bit and mounting therefor of durable and strong construction, particularly suitable for lightweight, low cost trench-digging machines. It is another object of the present invention to provide a digger-bit construction which is capable of efficiently digging and elevating loosened soil from a trench even under the most adverse operating conditions.

A further object of the present invention is to provide a digger-bit and mounting construction which includes novel structure for causing the bits to operate efficiently under varying soil conditions. It is also an object of the present invention to provide a digger-bit and mounting which are readily adapted to dig trenches of various widths.

It is a more detailed object of the present invention to provide a digger-bit construction which insures against loss of the bit in operation and precisely retains the bit in the desired operating position.

Other objects and aims of the present invention will become apparent as the following description of a preferred embodiment of my invention proceeds, in which:

Figure 1 is a bottom face view of a portion of an endless link chain with digger-bits and holders embodying the present invention assembled in normal operating position.

Fig. 2 is a side elevation of the assembly shown in Fig. 1 lowered into operating position relative to the forward wall of a trench.

Fig. 3 is a perspective of a single digger-bit.

Fig. 4 is an end view of a straight portion of endless chain with the digger-bits in normal position.

Fig. 5 is a side elevation partially in cross-section taken along the line 5—5 of Fig. 4.

Fig. 6 is a transverse cross-section of one of the digger-bit holders taken along the line 6—6 of Fig. 5.

Fig. 7 is a diagrammatic view of the relative position of the digger-bits arranged for digging loose, sandy soil.

Fig. 8 is a diagrammatic view of the relative position of the digger-bits arranged for digging hard, stony soil or clay.

While the invention is susceptible of various modifications and alternative constructions, I have shown in the drawings and will describe in detail the preferred embodiment, but it is to be

understood that I do not thereby intend to limit the invention to the specific form disclosed, but intend to cover all modifications and alternative constructions and uses falling within the spirit and scope of the invention as expressed in the appended claims.

Referring more particularly to the drawings, Figs. 1 and 2 show an endless chain 10 with digger-bits 11 and holders 12 mounted thereon.

10 The endless chain is of the common roller link type, having a series of transverse rollers 14 held in parallel spaced relationship by pairs of inside links 15 and overlapping outside links 16. Pins or rivets 18 passing through holes in the end portion of links 15, 16 and axial bores in the rollers 14 securely hold the parts of the chain in position.

Trenching machines adapted for using the endless chain type of digger are well known and a detailed description of their construction is not necessary to an understanding of the present invention.

An exemplary device is disclosed in the copending Schmidt application, Serial No. 755,825, assigned to a common assignee. Suffice it to say that the chain 10 is trained in an endless loop over a pair of spaced sprocket wheels 19 mounted on opposite ends of a beam 20. The beam is pivotally connected for vertical swing at one of its ends to a trencher frame which is supported for movement along the surface of the ground in the direction the desired trench is to be dug.

20 As shown in Fig. 2, the digger-bits 11 are mounted at uniformly spaced points on the loop of chain and project outwardly therefrom. A suitable source of power, such as a gasoline engine, drives the sprocket located adjacent the pivotal connection to the frame causing the chain to move the bits upwardly against the earth.

25 Preferably the forward movement of the trencher frame is coordinated with the speed of the chain to move the bits into the forward wall 40 of the trench at a uniform rate causing each bit to take the same size "bite" of earth. Lateral conveyors adjacent the upper end of the frame may be provided to carry the removed dirt to piles spaced outwardly from the top of the trench.

30 Considering now in detail the preferred embodiment of my invention, each digger-bit 11 comprises a shank portion 21 which forms a strong, rigid support for a cutting or blade portion 22 mounted on the forward end of the shank. The shank 21 of the bit has a regular polygonal cross-section which preferably is pentagonal, allowing positive angular positioning of the blade 22 with respect to the holder 12 for reasons which 35 will be explained presently. The blade portion

22 of the bit has a transverse forward cutting edge 23 of suitable length for the size and type of trenching machine with which the bit is to be used. I have found that a two inch blade is highly satisfactory for a lightweight machine such as that disclosed in the above copending application. As shown in the drawing, the blade of the bit has a chisel shape which is formed by a rearwardly extending triangular upper face 24 and a beveled lower face 25 extending downwardly and rearwardly from the cutting edge to a line of intersection with the opposite side of the shank. A slope of about 20° for the lower face 23 provides an efficient cutting edge. The lateral edges 26, 27 of the blade are necked inwardly providing side draft or relief for the bottom face 25 which commonly constitutes the working or leading face of the bit.

The bits 11 are positively and rigidly supported on the chain 10 by the holders 12 which are adapted for rapid, simple interchange and multiple positioning of the bits 11 and holders 12. The holders have a body portion or saddle 29 which overlies the chain, and a pair of mounting legs 30 which project downwardly from the saddle 29 along the sides of the chain. The legs 30 are spaced apart a distance equal to the spacing between a pair of outside links 16 so that a pair of outside chain links may be readily replaced by the legs 30 of the holders. The holders are connected to the chain and held in straddling position by transverse pins or connectors passing through holes in the legs spaced to correspond to the holes in the pairs of outside links 16 replaced by the holders. To provide for ready installation and removal of any holder, bolts 31 and nuts 32 are provided for this purpose. To prevent accidental loosening of the connectors, the nuts 32 are of the castle type and are fitted with cotter pins 33. If desired, the bolts 31 may be restrained from turning relative to the holders 12 by using bolts having a square or T-shaped head 34 engaged by a laterally extending rib 35 or the like on the outside of each leg 30.

Additional support for the digger-bit holders 12 is provided by rearwardly extending lugs or projections 36 formed integrally with the upper edge portion of the legs 30 of the holder. The lugs 36 project rearwardly to or slightly beyond the axis of the next adjacent roller 14 of the chain and have their bottom edges curved upwardly to conform to the contour of the following outside links 16. It will be apparent by reference to Fig. 5 that the lugs 36 resist rearward tipping forces on the holder and provide a third point of support greatly increasing the strength and evenness of operation of the digger chain.

Mounted on the saddle 29 of the holder 12 is a clamp or vise, indicated generally at 37, for securely gripping and retaining the shank 21 of the digger-bits 11. The clamp comprises a massive, column-like support of generally rectangular outline extending fore and aft for the length of the holder 12. The outer portion of the clamp is provided with a pair of opposed gripping jaws 38 forming a split sleeve with a longitudinal hole or bore 39 corresponding in cross-sectional contour and size with that of the shank 21 of the bit. The bore 39 is abruptly or sharply reduced in size at its trailing end portion to form a collar or abutment 40 which acts as a positive stop limiting the rearward movement of the bit in the holder. The jaws 38 of the clamp are drawn toward each other for applying gripping pressure to the sides of the shank 21 of the bit merely by

tightening a bolt 41 and nut 42 which are inserted in a transverse hole 43 drilled through the jaws of the clamp. A cotter pin 44 and castle nut 42 may be provided to prevent accidental loosening of the jaws 38 of the clamp.

A suitable angle of attack for the working face and edge of the bit 11, as well as for allowing clearance for the holders 12, is provided by sloping the bore 39 of the clamp outwardly from back to front from the saddle 29 of the holder. In the preferred embodiment an outward angle of about 20° from the saddle provides adequate clearance and presents the cutting edge of the bit at an angle for effective removal of dirt from the forward edge of the trench. The angle used in any particular construction will depend on the length of the bit, the amount of bevel on the working face, and the slope of the frame supporting the endless chain.

For digging a trench of greater width than that of an individual digger-bit, the holders 12 are adapted to provide increasing lateral offset of the bits 11. To accomplish this, the holders are mounted on the chain in a series beginning with a center holder 12a and followed by pairs of alternate right and left hand enlarging holders 12b, 12c, 12d. Such a series of holders is repeated throughout the length of the loop of digger chain to provide continuous digging of a trench having a width equal to the span of the digger-bits 11 in the widest pair of enlarging holders.

The digger-bits are relatively offset by varying the sidewise angular and bodily displacement of the clamping portions of the holders. The clamping portion of the center holder 12a is located directly over the saddle 29 and is aligned with the centerline of the chain so that a bit mounted in this holder will remove the dirt from the middle of the trench width. The clamps of the first pair of enlarging holders 12b are located over the saddle portions and are alternately angled laterally of the direction of movement of the chain. The amount of lateral angularity should be sufficient to give a substantial increase in trench width over the bit in the center holder 12a but should also allow some overlap between the paths of the center bit and the following pair of bits. I have found that a horizontal angle of about 15 degrees between the center line of the chain and the axis of the bore 39 is satisfactory for a bit having a two inch leading edge. The angular offset of the enlarging holders not only provides increased span but also positions the digger-bits relative to the cutting wall for more efficient removal of the dirt.

Greater lateral offset is provided by transverse bodily displacement of the clamping portions of the holders relative to the chain in addition to the angular offset described for the first pair of enlarging bits. Thus the second pair of enlarging holders 12c have the clamping portions located approximately above opposite sides of the holder, while the third pair of holders 12d has an opposed outward lateral extension 45 on the saddle to support the clamping portion. I have found that an overlap of about one-quarter of the width of the cutting edge is suitable for a two-inch blade so that the width of succeeding cuts will be approximately 2, 5, 8 and 11 inches. It will be appreciated, however, that the amount of overlap will depend on the particular dimensions and construction of the digger-bits and holders used.

Highly efficient digging action for various types

of soils and soil conditions is obtained with digger-bits and holders constructed in accordance with the present invention. As shown in Fig. 4, the digger-bits 11 are mounted in the holders 12 for normal digging operation of ordinary packed earth or loam. In this position the cutting edge 23 of the bit is substantially parallel to the transverse plane of the endless chain 10. Positive interference between the flat sides of the polygonal cross-sections of the shank 21 of the bit, and the bore 39 of the holder holds the bits in the desired angular position. It will be apparent, however, that the bit may be inserted in the holder with the blade 22 inclined at various angles with respect to the normal position by orienting the bit through the angle required to bring succeeding sides of the shank into parallel with the sides of the bore 39 of the holder.

A precise locking action retaining the bits in the various angular positions and restraining the bits against accidental longitudinal displacement and loss is provided by engagement between the sides of a transverse locking groove 47 formed in the shank of the bit and the tightening bolt 41. The bolt receiving hole 43 is positioned on the jaws 38 of the holder to intersect chordwise the surface of the bore 39, thereby causing the bolt 41 to lie at least partially within the path of movement of the shank of the bit. The groove 47 lies across one edge of the shank so that it mates with the receiving hole 43 when the bit is fully inserted into the holder and bears against the abutment or stop 40. To permit locking of the bit in auxiliary angular positions, additional locking grooves 48 intersecting adjacent edges of the shank are provided. In a given orientation of the bit, the tightening bolt 41 will engage, at least, one of these locking grooves 47, 48. Thus when the tightening bolt 41 is inserted into the clamp after the bit has been properly positioned, the shank of the bit is securely restrained against longitudinal and angular movement.

I have found that the digging of sandy, loosely packed soil is greatly improved by turning the beveled working face 25 of the bits mounted in the enlarging holders 12b, 12c, 12d inwardly toward the center of the holder as shown diagrammatically in Fig. 7. Hard, stony soils and clay, on the other hand, are effectively dug by orienting the digger-bits in the enlarging holders in the opposite direction, as shown in Fig. 8, with the beveled working face 25 angled outwardly from the adjacent side of the holder. In the preferred embodiment, the shank of the bit is pentagonal in cross-section, as above described, and permits the blade of the bit to be turned through an angle of about 72° to either side of the normal cross-wise blade position. In short, the angularity obtained by using the pentagonal bit permits highly effective working areas and angular relationships to be obtained for different types of soils with but a single bit and holder construction.

The invention obviously is not limited to constructions in which the enlarging holders are staggered alternately to the right and left, only the preferred embodiment being illustrated. The invention would, therefore, include constructions in which pairs of right and left hand holders are mounted side by side on a common body or saddle portion. The side by side position of such holders tends to balance the lateral twisting forces to which the digger chain is subjected by a single holder and bit. Such twisting forces, 75

of course, increase as the lateral offset of the holders is increased, making the side by side mounting particularly advantageous for pairs of holders having large digging span, say of eleven inches or more.

While it might be thought that the present construction of digger-bits and holders would be ineffective to elevate substantial amounts of earth out of the trench, the contrary is true. The present construction not only loosens the soil with great effectiveness but also carries the loosened material upwardly to the surface of the ground with a high degree of efficiency without resorting to the use of buckets or pockets of any kind. Moreover, the multiple position locking structure of the bits and holders enhances the digging characteristics of the chisel-like blade portions of the bits.

Non-clogging and self-cleaning operation of the chain is provided by vertical escape holes or ports located in the central portion of the saddle 29 of the holders. The flexing of the chain and the pressure of soil or dirt on the chain will force any material entrapped between the chain and the holder upwardly and outwardly through the escape holes 49. For the holders having the clamping portion 31 mounted directly over the saddle, additional transverse passages 50 are provided in the column-like body of the clamp to complete the escape path of the dirt from the underside of the saddle 29 to the outside of the holder.

I claim as my invention:

1. For use with a trenching machine having an endless loop of digger chain with a series of digger-bit holders mounted thereon, each of said holders having a clamp defining a pentagonal opening with an abrupt shoulder extending into the latter near the trailing end of said clamp and a transverse bolt lying at least partially within said opening, a digger-bit having a shank portion of pentagonal cross section of a size adapted to be gripped in said clamp, and a blade portion, said blade portion having a transverse cutting edge and a bevelled lower working face extending rearwardly and downwardly from said cutting edge to the opposite side face of said shank portion, said blade portion also having a rearwardly extending upper face of triangular shape to provide side draft for said lower working face, the shank portion of said digger-bit having a plurality of transverse grooves spaced from the rearward end of said digger-bit a distance corresponding to the distance between the transverse bolt and the shoulder of said holder to locate positively the blade of said digger-bit in a selected one of a plurality of predetermined angular positions relative to said holder.

2. For use with a trenching machine having an endless loop of roller chain, the chain having pairs of over-lapping inside and outside links, the combination comprising a bit having a blade portion and a polygonal shank portion with transverse grooves in the ridges thereof, a holder for said bit having a saddle portion and downwardly projecting legs, said legs having spaced holes therein arranged for connecting said holder to the chain in place of a pair of outside links of the latter, said legs having rearwardly extending projections adjacent their upper ends shaped to bear against the upper edge of the next following outside links of the chain, said holder also having an opening positioned centrally of said saddle, clamping means on said holder for gripping the shank portion of said bit, said clamping means including an upwardly extending column

member integral with said saddle of the holder and a pair of gripping jaws in the upper end portion thereof, said jaws defining a polygonal bore corresponding in shape to that of the shank portion of the bit, said column and jaws being positioned on said saddle to permit free passage of earth through the central opening in the latter, and a removable tightening bolt positioned transversely of said jaws and lying partially within the bore defined by the jaws to engage the sides of one of the grooves of said shank portion of the bit.

GLENN W. McININCH.
